PAPER TUBE AND METHOD OF MAKING

Leonard A. Young, Detroit, Mich.

Application July 23, 1938, Serial No. 220,874

9 Claims. (Cl. 93—94)

This invention relates to improvements in paper tubes and method of making.

The main objects of this invention are:

First, to provide a paper tube which may be very economically and rapidly produced.

Second, to provide a paper tube which is very rigid in proportion to the amount of material or stock.

Third, to provide a paper tube which is well adapted for use as a garment hanger strut.

Fourth, to provide a method of making paper tubes and similar structures having the advantages above indicated.

Objects relating to details and economies of the invention will appear from the description to follow. The invention is defined and pointed out in the claims.

Preferred embodiments of the invention are illustrated in the accompanying drawings, in which,

Fig. 1 is a fragmentary view illustrating various steps in the manufacture of a preferred embodiment of my invention.

Figs. 2, 3, 4, 5, 6 and 7 are enlarged sections on lines 2—2, 3—3, 4—4, 5—5, 6—6 and 1—1 of Fig. 1 illustrating successive steps of my method, Fig. 7 illustrating the completed tube.

Fig. 8 is a plan view of a section of the tubing of my method cut to form a garment hanger strut.

Fig. 9 is a conventionalized side elevation of a machine or apparatus for practicing the steps of my method when a single strip of paper is employed as distinguished from the two strips shown in Fig. 1.

Figs. 10 to 14 inclusive are enlarged fragmentary sectional views on lines corresponding to line 10—10, 11—11, 12—12, 13—13, 14—14 respectively of Fig. 9 illustrating successive steps of the method.

Fig. 15 is a side elevation of a garment hanger embodying the strut of this invention.

One of the main objects of my invention is to provide a paper strut for garment hangers such, for example, as illustrated in my Patent No. 2,011,265 issued August 13, 1935, or the Oldham Patent No. 2,025,887 issued to me as assignee under date of December 31, 1935, which may be very rapidly and economically produced and possesses great rigidity in proportion to the amount of stock contained therein.

Paper tubes have heretofore been produced by spiral winding and by convolute winding and while the spiral wound tubes may be rapidly produced they are easily broken when subjected

to lateral stresses. The convolute wound tubes are stronger but are quite expensive and production is quite expensive and requires a relatively large amount of time in production thereof; also they require a fairly good quality of paper. My improved struts and paper tubes may be very rapidly produced of a relatively low or poor grade of paper and they are very strong and rigid.

Referring to Figs. 1 to 7 inclusive, I illustrate a preferred form of my invention both as to product and method. I provide a plurality of strips of paper 1 and 2 which are arranged in a superimposed relation, the strip 1 being substantially wider than the strip 2. These strips of paper are coated on one side with an adhesive, preferably a quick drying adhesive. The paper and the adhesive are of such a character that when the adhesive is applied to the strips there is a substantial penetration of the adhesive into the paper as well as the surface coating which is indicated by the stippling 3 in the drawings.

The adhesive is applied to the strip 1 before the strip 2 is superimposed thereon so that the strips are adhesively secured together in their superimposed relation. The superimposed strips are first folded longitudinally upon themselves, as shown in Fig. 3, and it will be noted that this brings the adhesive bearing surfaces of the strip 2 together. The wider strip is then folded down upon the previously folded double strip to the position shown in Fig. 4 with one edge of the strip 1 projecting to provide a joint flap 4. The multiply strip or body designated by the numeral 5 is then rolled longitudinally upon itself, preferably by a series of successive operations as shown in Figs. 5, 6 and 7 into the completed tube 6 with the joint flap 7 within the tube and overlapping the joint 8 resulting from the abutting edges of the multiply strip being brought together. These abutting edges are preferably adhesively secured together although for many uses of the tube that is not essential.

It will of course be understood that the folding to provide a multiply strip or body 5 takes place before the adhesive is set and this is also true of the rolling or tube-forming strips. With the adhesive in its unset or plastic condition, the plies readily slip upon one another as the multiply body or strip is rolled into the tube and when the cement or adhesive is set they retain their shape, the adhesive serving as a stiffening medium.

There are two advantages in employing a relatively poor or cheap grade of paper, one being

the economy of the material itself and the other that substantial amounts of the adhesive are absorbed thereby even though the manufacturing steps are being carried on at high speed and 5 there is a sufficient quantity of the adhesive present to serve as a stiffening medium so that the final product is capable of sustaining very substantial loads even when of comparatively light stock. It will be understood that in the 10 accompanying drawings I have not attempted to show the parts in relative proportions as it is impractical to do that and still provide clearness.

The completed tube 6 may be cut into suitable lengths to provide a strut 9, as shown in Fig. 8, 15 and I preferably notch the ends as at 10 to receive the arms of a hanger yoke such as indicated in the patents referred to.

In Fig. 9 I illustrate a method of forming a tube or strut from a single strip of paper 11 as 20 distinguished from a plurality of strips, this strip 11 being drawn from a roll 12 between a pair of rollers 13 and 14, the roller 14 being a glue or adhesive applying roller receiving the glue or adhesive from the tank 15. A pair of folders 25 are conventionally shown at 16 and 17, the folder 16 bringing the strip to the position shown partially by dotted lines in Fig. 10 and the folder 17 bringing it to the position shown by full lines in Fig. 10. The folders are not illustrated, as 30 folders are known, particularly in the textile manufacturing art.

From the folder 17 the partially folded strip designated by the numeral 18 is passed between a pair of rollers 19 where it is brought into the 35 completely folded strip 20. The strip 20 then passes to a pair of coating forming rollers 21 and 22, see Fig. 12, in which the multiply strip 20 is partially conformed or rolled longitudinally upon itself, this being preferably merely a matter 40 of turning the edges 23. It is then passed to the coating rollers 24, 25 when it is brought to a channel section. It is then passed to the rollers 26 and 27 which brings it to the form of the completed tube 28. Between the rollers 24, 25 and 26, 27 is a reducing gauge or die 29 which 45 brings the edges together somewhat for the final rolling operation and also smooths the exterior surface.

A glue applying device 30 is disposed in advance of the sizing gauge 29 to apply glue to the 50 edges of the multiply strip or at least one edge thereof so that when they are brought together to the position shown in Fig. 14 they are adhesively secured together. It will be understood 55 that the meeting surfaces as indicated by the lines 31 and 32, Fig. 14, are coated with adhesive. No attempt is made in these figures to maintain the proportion.

After passing the rollers 27, the completed 60 tube, indicated at 33, passes through a shear block 34 where it is severed by the cutter 35 co-acting with the shear block into suitable lengths to form the struts 9.

Fig. 15 illustrates the manner of mounting the 65 strut in the wire yoke 27 of the type described.

When a plurality of strips are used, I preferably for the sake of economy and also to permit substantial impregnation use a rather porous soft grade of paper which permits the adhesive to 70 penetrate substantially even when the method is practiced at a high rate of speed. When multiply strips are used, the strip 1 may be, if desired, of a better grade of paper than the strip 2.

While my improved tubes and method were 75 intended primarily by me for the manufacture of

paper struts and hangers and the production thereof, my method may be used in the production of tubes.

Tubes embodying my invention have a wide application and larger tubes, for example mailing tubes, storage tubes and the like, cores for winding paper, and various other uses, may be economically produced. I have not attempted to illustrate the various adaptations as it is believed that this disclosure will enable those skilled in the art to which my invention relates to embody or adapt the same as may be desired.

Having thus described my invention, what I claim as new and desire to secure by Letters Patent, is:

1. A strut for garment hangers comprising a plurality of strips of paper disposed in superimposed relation and adhesively secured together with the edge of the outer strip projecting beyond the other, the superimposed strips being folded longitudinally and adhesively secured together and rolled longitudinally into a tube with the projecting edge overlapping the joint of the tube. 20

2. A paper tube comprising a plurality of strips of paper disposed in superimposed relation and adhesively secured together throughout in superimposed position, the superimposed strips of paper being folded longitudinally into a multiply body and conformed into a tube with the edges 30 of the body abutting and adhesively secured together.

3. A paper tube comprising a strip of paper folded longitudinally upon itself into a multiply strip, the paper being substantially impregnated and coated on the meeting faces of the plies with adhesive constituting a stiffening medium, the multiply strip being rolled longitudinally into a tube. 35

4. A paper strut for garment hangers comprising a strip of paper folded longitudinally upon itself into a multiply strip and the multiply strip conformed into a strut of tubular section, the paper being substantially impregnated and coated on the meeting faces of the plies with adhesive, the adhesive constituting a stiffening medium. 40

5. The method of producing paper tubes comprising the steps of superimposing and adhesively securing together strips of paper, one strip being wider than the other, folding the superimposed strips longitudinally into a multiply body with the edge of the wider strip projecting beyond one edge of the multiply body, and conforming the multiply body by rolling longitudinally upon itself to bring the edges of the body into abutting relation with the said projecting edge overlapping the joint. 55

6. The method of producing paper tubes comprising the steps of superimposing and adhesively securing together strips of paper in superimposed position, folding the superimposed strips longitudinally into a multiply body with a ply of one strip projecting beyond one edge of the multiply body to provide a projecting joint flap, and conforming the multiply body by rolling longitudinally upon itself to bring the edges of the body into abutting relation with the said projecting flap overlapping the joint. 60

7. The method of producing tubes comprising the steps of applying adhesive to one side of a strip of paper and substantially impregnating the strip with the adhesive, folding the strip longitudinally upon itself into a multiply strip with the adhesive bearing surfaces interiorly of the 70

multiply strip, and rolling the multiply strip longitudinally into a tube prior to the setting of the adhesive.

8. The method of producing tubes comprising the steps of folding a strip of paper longitudinally upon itself into a multiply strip and adhesively securing the plies together, and rolling the multiply strip longitudinally into a tube prior to the setting of the adhesive.

9. A paper strut for garment hangers comprising a strip of paper folded longitudinally upon itself into a multiply strip with a ply projecting at one edge of the multiply strip to provide a joint flap, the multiply strip being conformed into a strut of tubular section with the edges thereof abutting and the flap overlapping the joint.

LEONARD A. YOUNG.
